UNITED STATES PATENT OFFICE.

DUDLEY J. MORTON, OF MILFORD, CONNECTICUT.

DESIGN FOR A DOLL OR MANIKIN.

Application filed October 1, 1921. Serial No. 504,788. Term of patent 14 years.

To all whom it may concern:

Be it known that I, DUDLEY J. MORTON, a citizen of the United States, residing at Milford, in the county of New Haven and State of Connecticut, have invented a certain new, original, and ornamental Design for Dolls or Manikins, of which the following is a specification, reference being had to the accompanying drawing, forming a part thereof.

The figure is a view in elevation of a doll or manikin showing my new design.

I claim:

The ornamental design for a doll or manikin as herein shown.

DUDLEY J. MORTON.
